G. H. E. Lyons,
INVENTOR
BY *Victor J. Evans*
ATTORNEY

UNITED STATES PATENT OFFICE

GEORGE H. E. LYONS, OF BRONX, NEW YORK

CLIP OR BINDER FOR PAPER SHEETS

Application filed March 18, 1930. Serial No. 436,859.

The purpose of this invention is the provision of means whereby a plurality of sheets of paper, such as bills, memorandums, etc., may be connected together either in sequence or otherwise in an easy and expeditious manner, and whereby the several sheets may be individually detached without disturbing the remaining sheets.

It is also my purpose to provide a device for this purpose whereby the individual sheets are impinged in the body of the clip or holder and held in tight contacting relation by spring means that is carried by the cover of the clip or holder.

I also aim to produce an article for this purpose which shall be of an extremely simple construction, cheap to manufacture, thoroughly efficient for its purpose, and wherein the paper sheets are securely held but readily detachable.

To the attainment of this and other objects, the invention consists in the improvement as hereinafter described and definitely claimed.

In the drawing:

Figure 1 is a plan view of the improvement in applied position.

Figure 2 is a sectional view approximately on the line 2-2 of Figure 1.

Figure 3 is a detail sectional view taken on the line 3-3 of Figure 1.

Figure 4 is a detail sectional view to illustrate an adjustable impaling element.

Figure 5 is a perspective view of the device, with the top or cover removed.

Figure 6 is a similar view of the top or cover.

Figure 7 is a sectional view on the line 7-7 of Figure 2.

Figure 8 is a detail sectional view to illustrate the removable impinging element, which may be considered a preferred form of the improvement.

The improvement is preferably wholly constructed of metal to include a triangular base or body and a similar shaped top or cover. The metal is comparatively thin and both the body and top or cover are preferably stamped from single pieces of material.

The body includes a base 1 formed with

points of the sides are preferably formed with a connecting element 3.

The base 1, at preferably the center thereof has an upstanding impaling element. If desired the impaling element may include a threaded stud 4 which is fixed on the base and has screwed thereon the socket portion of a pointed member 5. However, and as disclosed by Figure 8 of the drawing the base 1 may have a thickened portion provided with a threaded opening in which is screwed the threaded part 6 of an impaling element 7. The impaling element has a flared head 8 received in a countersunk opening in the under face of the base 1.

The sides 2, adjacent to the top and open front of the body, have apertures 9 therein for the reception of lugs or trunnions 10 on the corners of a triangular top or cover 11. The widened edge of the cover, between the lugs or trunnions 10 is concaved inwardly, as at 12, the top of the cover being provided with spaced guides 13 for a removable latch 14 formed with a bulged or headed portion 15. The latch is movable beneath the element 3 on the body when the cover is brought to a closed position.

The under face of the cover 11 is approximately centrally formed with rounded lugs or ears 16 for the reception of one of the end coils of a helical spring 17.

The element 15 on the latch 14 serves as a handle which will assist the operator in swinging the cover to open position, although the spring 17 materially assists in this operation. One or any desired number of paper sheets 18 are arranged in the body and secured therein by the impinging element. These sheets are effectively sustained in the body when the cover 11 is swung to closed position, and latched on the body, the spring 17 exerting a downward pressure upon the sheets. The impinging element may be adjusted to accommodate a large number of sheets of paper held together by the improvement, and the separate and desired sheets may be detached by removing or partly removing the impinging element 7 disclosed by Figure 8 of the drawing. The several sheets may be formed with alining aper-

tures so that the same may be easily and quickly arranged over the impinging element, and it is thought that the construction, operation and advantages of the improvement will be apparent and will be appreciated by those skilled in the art to which the invention relates without further detailed description. The concaved edge or end 12 permits of the cover being swung to open position without contacting with the paper sheets 18 and the cover 11 may be readily latched on and readily swung away from the body to permit of the insertion or the removal of the sheets. Obviously I do not wish to be restricted to the precise details herein set forth, and, therefore, hold myself entitled to make such changes therefrom as fairly fall within the scope of what I claim.

Having described the invention, I claim:

23. 1. A holder comprising a body to receive the corner of a plurality of sheets of paper, an impaling element on the body to penetrate the sheets of paper, a top hinged to the body and when in one position adapted to overlie the impaling element to prevent removal of the sheets of paper therefrom, means for securing said top in said position, and a tension means on the top to bear against the sheets of paper when said top is in said position.
28. 2. A holder comprising a flanged triangular-shaped body to receive the corner of a plurality of sheets, sheet-penetrating means on the body, a top hinged to the body and overlying said means and the corner of the sheets, means detachably securing the top to the body, and tension means carried by the top and adapted to bear against the sheets.
33. 3. A holder comprising a flanged triangular-shaped body to receive the corner of a plurality of sheets, sheet-penetrating means on the body, a top hinged to the body and of substantially triangular shape and overlying said means and the corners of the sheets, means detachably securing the top to the body, and a coiled spring having one end secured to the body and its other end bearing against the sheets.
38. 4. A holder comprising a triangular shaped body, side flanges on the converging edges of said body and integrally connected to cooperate with the body in receiving the corner of a plurality of sheets, sheet penetrating means carried by said body, a top hinged to said flanges and adapted to overlie the sheet penetrating means, a lip connecting said flanges, a slidable latch carried by said top to engage the lip, and tension means carried by the top and bearing against the sheets engaged by the sheet penetrating means.
43. 5. A holder comprising a flanged body having an open end and an open top, an impaling post carried by the body, a top hinged to the body for closing the open top thereof,

a slidable latch carried by the top for detachably securing the latter to the body, and a helical spring carried by the top and adapted to encircle the post when said top is in a position for closing the body.

6. A holder comprising a triangular shaped body, side flanges on said body, a connecting element between the flanges, said flanges each having a hole therein adjacent its outer end, an adjustable impaling post on the body, a flat triangular cover plate having trunnions journaled in the openings in said flanges, a longitudinally movable latch on the cover plate to engage with the connecting element, a handle portion on said latch, and a pressure spring secured to the under face of the cover plate.

In testimony whereof I affix my signature.

GEORGE H. E. LYONS.
